HERBERT D. WOOD, OF PHOENIX, NEW YORK.

TOILET-PAPER HOLDER.

1,104,284.

Specification of Letters Patent.

Patented July 21, 1914.

Application filed March 2, 1914. Serial No. 821,946.

To all whom it may concern:

Be it known that I, HERBERT D. WOOD, of Phoenix, in the county of Oswego, in the State of New York, have invented new and 5 useful Improvements in Toilet-Paper Holders, of which the following, taken in connection with the accompanying drawings, is a full, clear, and exact description.

This invention relates to certain improvements in toilet paper holders involving the use of a bracket adapted to be secured to the wall and a substantially flat paper reel journaled in a horizontal position upon the bracket and counter-weighted to assume an 10 edgewise position vertically, so that the toilet paper, which is slit or cut transversely at intervals from its opposite longitudinal edges, may be supported in a similar position with its free end hanging vertically 15 from the reel, preferably at the rear side thereof. In this class of holders, the transverse slits in the paper occur at regular intervals so as to always appear at the front and substantially midway between the lower 20 and upper edges of the reel, which, together with the bracket, are provided with co-operative stops to limit the rocking or oscillatory movement of the reel to substantially one-half of a complete revolution, produced by 25 grasping the lower end of the paper between the fingers and drawing it downwardly thereby bringing the slit of the first section of the paper to be torn off at the back of the reel substantially midway between its lower 30 and upper edges. I have found, however, that when the reel is limited by the stops to approximately a half revolution, or less, the portion thereof which is to be torn off 35 draws tightly against the back of the main body of the roll and that in order to tear the paper at the slit, it is necessary to give the end of the paper a side draft, which frequently results in tearing the paper between the first 40 slit and the end thereof, which of course is objectionable and results in waste of paper, aside from the inconvenience to the operator.

The primary object, therefore, of my invention is not only to position the limiting stops so as to allow the reel to rotate through more than a half of a revolution, or rather, beyond a vertical edgewise position after having been moved through an arc of 180° so that the reel will incline upwardly and rearwardly from its lower edge when brought to a stop, but also to cause one end

of the reel to tilt upwardly thereby placing the greater tension during the downward pull upon the paper upon the raised edge of such paper, whereby it is more easily torn off at the transverse slit running transversely from such elevated edge, the rocking of the reel beyond a vertical edgewise position serving to clear the free end thereof from the main body of the roll to additionally facilitate the tearing off along the transverse slit.

Other objects and uses relating to specific parts of the device will be brought out in the following description.

In the drawings—Figure 1 is a perspective view of a toilet paper holder embodying the various features of my invention. Fig. 2 is a front face view of the same device showing one of the bearings and paper roll 75 in section, the reel being shown in elevation. Fig. 3 is an end view of the same device showing by dotted lines the position of the reel when tearing off a section of paper.

The device shown comprises a bracket 80 —1— having a vertically disposed back plate —2— provided with slots or apertures —3— for receiving screws —4— by which the bracket may be secured to a wall or other convenient support, the lower edge of 85 the back plate being provided with forwardly projecting arms —5— spaced a sufficient distance apart to receive between them a paper reel —6—. This reel is substantially flat in cross section and rectangular in face view, and is provided with central end journals or pintles —7— and —8— journaled in suitable bearings —9— and —10— in the front ends of the arms —5—, said reel having its normal lower 90 side weighted to cause it to assume a normal vertical position, or rather, to normally stand edgewise vertically with freedom to be rocked in either direction.

One of the pintles, as —7—, is preferably 100 formed upon the outer end of an axially movable bolt —11— having its inner end projecting into an opening —12— in the central portion of the reel for accessibility when the paper is removed to permit the 105 bolt to be drawn by hand inwardly, thereby displacing the pintle —7— from its bearing and permitting the removal of the reel from the bracket, the central portion of the sliding bolt —11— being surrounded by a coil 110 spring —13— which serves to retract the bolt or rather to force it to its operative

position in the bearing —9— when the reel is replaced in the frame or bracket.

A roll —14— of toilet paper is wound more or less tightly around and upon the reel so as to assume substantially the same transverse form thereof and is slit transversely at —15— at regular intervals throughout its length and extending inwardly from its longitudinal edges, thereby dividing the roll into a series of sections capable of being easily torn off, each section having a length substantially equal to half of the perimeter of the reel and arranged so as to bring each slit normally at the front of the roll midway between the lower and upper edges of said reel, whereby when the reel is operated through approximately a half revolution by drawing down upon the lower end of the paper, the first slit will be brought to the rear of the reel and substantially midway between its lower and upper edges with the free end of the paper hanging downwardly some distance below the lower edge of said reel, where it may be conveniently grasped between the fingers and torn off at the slits.

Suitable means is provided for limiting the rocking movement of the reel from its normal position through an arc of a little more than 180° , or sufficient to allow the free end of the paper to hang from the top edge of the reel clear from the main body of the roll, and for this purpose I have provided one of the arms, as the right hand arm —5—, of the bracket with a limiting stop —16— disposed in the path of movement of a coöperative stop —17— on the adjacent end of the reel at one side of the corresponding pintle —8—, the stop —16— being preferably made of rubber to form a yielding and noiseless abutment for the coacting stop —17—, said stops being arranged so as to allow the reel to rotate somewhat more than a half revolution for the purpose described.

The means for tilting the reel longitudinally at the end of its rocking movement for the purpose previously referred to, consists in elongating the bearing —10— for the adjacent pintle —8— so as to form an upwardly and forwardly curved slot —18— of sufficient length to allow the adjacent end of the reel to move forwardly and upwardly to a plane above that of the opposite end when the stop —17— is brought into co-operative engagement with its abutment —16—, so that the abutment constitutes a separate fulcrum at the rear of the pintle —8— about which the adjacent end of the reel may be additionally rocked by the engagement of the stop —17— therewith, in the manner shown more clearly by dotted lines in Fig. 3. This upward tilting of one end of the reel throws the free end of the paper from a vertical position, that is, it

elevates the upper edge of the roll nearest the bearing —10— some distance above the opposite edge so that when the free end of the paper is grasped between the fingers in the act of drawing it down and thereby unwinding it from the reel, which also affects the rocking of the reel from its normal position in the manner described, the greatest tension will be placed upon the elevated edge of the paper, thereby causing it to tear at the slit with greater facility and with less liability of tearing the paper at other portions than the slit, which results in a great saving of the paper and less annoyance to the operator, it being understood that after each section of paper is torn off the reel with the roll thereon returns to its normal position, leaving the free end of the paper hanging from the upper edge of the reel along the rear side thereof and downwardly some distance below the same, the inclined slot in the bearing —10— causing the adjacent pintle to return to its normal position against the rear end of the slot.

The operation of my invention will now be readily understood upon reference to the foregoing description and the accompanying drawings, and although I have shown specific means for affecting the upward tilting of one end of the reel by the downward draft upon the free end of the paper when the reel reaches the limit of its rocking movement, it is evident that this construction may be modified without departing from the spirit of my invention and therefore I do not wish to limit myself to the exact structure shown and described.

What I claim is:

1. A toilet paper holder comprising a support having end bearings, one of which is elongated, a reel journaled in said bearings, and coöperative means on the support and reel for causing said reel to shift its position in the elongated bearing as the paper is unwound therefrom.

2. A toilet paper holder comprising a bracket having end bearings for a reel, one of the bearings being elongated and inclined, a reel journaled in said bearings, and coöperative means on the bracket and reel for causing one end of the reel to travel up the inclined bearing as the paper is unwound from the reel.

3. A toilet paper holder comprising a bracket having a pair of arms spaced apart and provided with journal bearings, one of which is inclined upwardly and forwardly, a reel journaled in said bearings and normally resting at one end against the lower end of the inclined bearing, and coöperative stops on the ends of the reel and bracket adjacent the inclined bearing for limiting the rocking movement of the reel and causing its adjacent end to ride up the inclined bearing as the paper is unwound.

4. A toilet paper holder comprising a support, a reel journaled on the support and normally resting in a horizontal position, and cooperative means on the support
5 and reel for lifting one end of said reel from its normal position when the paper is unwound therefrom.

In witness whereof I have hereunto set my hand this 16 day of February, 1914.

HERBERT D. WOOD.
